UNITED STATES PATENT OFFICE.

WALLACE E. SHAFFER, OF DENVER, COLORADO.

GAUGE COCK.

Application filed August 9, 1928. Serial No. 128,289.

My invention relates to gauge-cocks for steam boilers, and more particularly to improvements in gauge-cocks of the type in which a weighted lever-handle carries a valve which normally closes an escape-orifice in a screw-nozzle connected in an opening of the boiler near or at the water-level thereof.

It is an object of the invention to provide in connection with the weighted handle, a valve which may be readily renewed while the gauge-cock is in place on the boiler and a further object is to provide the stationary screw-nozzle of the device with a valve-seat which may be detached and replaced while there is pressure in the boiler, without escape of steam or water.

With the above and other objects in view my invention consists in the construction and arrangement of parts illustrated in the accompanying drawings in which like parts are similarly designated throughout the views and in which

Figure 1 represents a bottom view of the improved gauge-cock,

Figure 2, a longitudinal section taken on the line 2—2 Figure 1,

Figure 3, a transverse section along the line 3—3 Figure 2, looking in the direction of the arrows drawn across the line,

Figure 4, a similar section taken on the same line but looking in the opposite direction, and

Figure 5, a fragmentary sectional view of the portions of the members of the device at which they are joined together, showing the method of obstructing the passage of fluid from the boiler while the valve seat or the valve are being removed and replaced.

The reference numeral 5 designates the wall of a boiler, provided with a screw-threaded opening 6 for the connection of the nozzle-member of the gauge-cock. This nozzle-member comprises a body having a screw-nipple 8 for its connection in the opening of the boiler-wall, and a forwardly projecting lug 9 for the pivotal connection of the lever-handle hereinafter to be described.

The body has a longitudinal bore of different diameters, the outer portion of which is screw-threaded for the application of a headed screw-plug 10 which has a bore 12 in axial alinement with the other.

The plug provides a valve-seat for a valve mounted on the lever-handle hereinbefore referred to, and its bore 12 is of larger diam-

eter than the immediately adjoining portion 13 of the nozzle-bore for a purpose hereinafter to be described. The lever-handle of the device consists of an elongated body 14 weighted as at 15, and having at one end a recess 16 to admit the forwardly projecting lug 9 of the nozzle-member.

The lug and the side-walls of the recess have registering openings through which extends a cotter-pin 17 for the pivotal connection of the lever-member with the nozzle-member. The body of the lever member has a longitudinal passage partially screw-threaded for the adjustable connection of a valve which cooperates with the valve-seat of the screw-plug to normally obstruct the escape of steam or water from the boiler through the bore of the nozzle-member.

The valve comprises a stem 18 screw-threaded at one end for its connection with the screw-thread of the lever body, and provided with a head 20 to facilitate its rotary adjustment. A nut 19 on the threaded portion of the stem engages the end of the lever-body to lock the valve in its adjusted positions.

The valve proper consists of a pointed stud 21 which is connected in a screw-threaded socket at the end of the stem, by means of a correspondingly threaded nipple 22 of reduced diameter. The stud thus connected, is continuous with the stem and in axial alinement with the same and its point fills the slightly chamfered end portion of the bore of the plug on the nozzle-member of the device when the lever-member of the same is in its normal position.

In the operation of the gauge-cock, the valve is held in contact with its seat by the weight of the lever and when it is desired to test the height of the water in the boiler the lever is lifted so as to separate the valve from the seat and thereby permit the escape of steam or water through the opening of the nozzle.

The valve is adjusted to its proper closing position by rotation of the threaded stem and it is secured in its adjusted position by means of the lock nut.

When it is desired to remove either the valve or the plug while the gauge is in its operative condition, when one or both of the parts have become defective by wear or breakage, the passage of steam or water through the bore of the nozzle is stopped by the insertion of a pin 23 into said bore through the relatively larger bore of the screw-plug as illus-

trated in Figure 5. The pin, which may be of metal or wood, when thus positioned, obstructs the outflow of steam or water and the plug or the valve-stud or both these parts 5 may be removed and replaced under all conditions.

A steam and water tight closure may thus be maintained at all times either by adjustment of the valve or by replacement of the 10 valve-stud or the plug providing the valve-seat, and while the means employed for this purpose, as shown in the drawings, are preferred by reason of their apparent efficiency and simplicity of construction, it will be understood that minor changes in the structural details may be resorted to without departing from the spirit of the invention.

What I claim and desire to secure by Letters Patent is:—

20 1. A gauge-cock of the character described comprising a nozzle-member adapted for

connection with a boiler and having a passage for the escape of fluid from the boiler, a removable plug on the nozzle-member, having a bore of relatively larger diameter 25 throughout alined with the passage of the same, a pivoted lever-member, and a valve on the lever-member, adapted to close the bore of the plug.

2. A gauge-cock of the character described 30 comprising a nozzle-member adapted for connection with a boiler and having a passage for the escape of fluid from the boiler, a screw-threaded plug on the nozzle-member having a bore of relatively larger diameter 35 alined with the passage of the same, a pivoted lever-member, and a valve on the lever-member, adapted to close the bore of the plug.

In testimony whereof I have affixed my 40 signature.

WALLACE E. SHAFFER.
